United States Patent Office

Des. 196,502
Patented Oct. 8, 1963

196,502

SHAVER

Raymond A. Somers, Fairfield, and Raymond T. Cassidy,
Stratford, Conn., assignors to Sperry Rand Corporation,
New York, N.Y., a corporation of Delaware

Filed June 18, 1962, Ser. No. 70,597

Term of patent 14 years

(Cl. D22—3)

FIG. 2

FIG. 1

FIG. 4

FIG. 1 is a front elevation of a shaver showing our new design, the side opposite thereto being similar in appearance;

FIG. 2 is a side elevation as seen from the right of FIG. 1, the side opposite thereto being similar in appearance;

FIG. 3 is a top view thereof; and

FIG. 4 is a bottom view thereof.

The essential features of the design reside in the portions shown in solid lines on the drawings.

We claim:

The ornamental design for a shaver, substantially as shown and described.
